By his Attorney # UNITED STATES PATENT OFFICE

FRANK J. SPRAGUE, OF NEW YORK, N. Y.

ELECTRIC MOTOR.

SPECIFICATION forming part of Letters Patent No. 372,823, dated November 8, 1887.

Application filed April 18, 1887. Serial No. 235,149. (No model.)

To all whom it may concern:

Be it known that I, FRANK J. SPRAGUE, of the city of New York, in the county and State of New York, have invented a certain new and useful Improvement in Electric Motors, 5 of which the following is a specification.

My invention relates to the driving of ventilating fans or blowers by electric motors; and my object is to produce a cheap, simple, and 10 efficient arrangement and construction for this purpose.

My invention consists in the novel devices and combinations of devices employed by me in accomplishing the above-named object, as 15 hereinafter set forth and claimed.

In the accompanying drawings, Figure 1 is an end view of a motor, fan, and inclosing-case embodying my invention; and Fig. 2, a section on line 2 2 of Fig. 1, with the shaft, the commutator-cylinder, and the legs of the field-magnet in elevation.

A is an annular iron case, open at both ends, and preferably of sheet-iron, and having heavy rims B B', to which the sheet-iron portion A is 25 secured.

C is the shaft carrying the motor-armature D and the fan E. At the fan end of the shaft it is adjustably supported by means of screw-bolts a a', passing through a supporting ring 30 or hub, b b, carried by spokes b' b'. Bolt a sets into a cap, c, through both ends of which the shaft passes and turns. Bolt a' sets against an inner bearing, d, on the shaft. By adjusting these screw-bolts the shaft and the fan are 35 centered in the case. The other end of the shaft is journaled between hangers e e of non-magnetic metal, extending from the pole-pieces f f of the field-magnet of the motor. The hangers have concave bearing-surfaces, and the

40 bushing g has a corresponding concave surface, as illustrated at h, whereby a ball-and-socket joint is formed at this end of the shaft, so that it adjusts itself in accordance with the adjustment at the other end. After the shaft is properly adjusted the adjusting-screws a a' are secured rigidly by the locking-nuts i. The fan-blades E are secured to the shaft in the usual or any suitable manner. The armature D is 45 of the ring form, which is most convenient in this form of apparatus.

F F are the wire-wound cores of the field-magnet of the motor, having the pole-pieces f f, between which the armature D revolves.

The cores are bolted each to one of the iron brackets G G, which extend across the rim B 55 of the case, each having an extension, H, at its middle part to which the cores are secured. Both cores being thus attached to the case, said case forms the yoke or back piece of the magnet. This provides a very simple and at the 60 same time effective construction, the necessity of providing a special back piece for the magnet being done away with.

The whole arrangement is a very simple and economical one, all unnecessary parts being 65 done away with, the motor and fan both being in the same case and on the same shaft, and the case itself providing supports for the shaft.

The commutator-brushes and the electrical connections of the motor are not shown in the 70 drawings. They may be of any efficient character.

What I claim is—

1. The combination of an iron inclosing-case, an electric motor and a fan in said case, 75 the field-magnet cores of the motor being attached to said case, whereby said case forms the yoke or back piece of said magnet, substantially as set forth.

2. The combination of an annular iron inclosing-case, a shaft extending from end to end of said case, a fan and an electric-motor armature on said shaft, and field-magnet cores extending in opposite directions from the armature and attached to the case, substantially as 85 set forth.

3. The combination of an iron inclosing-case, an electric motor and a fan in said case, and brackets extending across said case, to which the cores of the field-magnet of the motor are respectively connected, substantially 90 as set forth.

4. The combination of an inclosing-case, an electric motor and a fan in said case on the same shaft, said shaft having bearings at one 95 end provided with means for laterally adjusting the shaft, and ball-and-socket bearings at the other end, substantially as set forth.

This specification signed and witnessed this 15th day of April, 1887.

FRANK J. SPRAGUE.
